UNITED STATES PATENT OFFICE.

WILLIAM B. PEIRCE, OF CORAOPOLIS, PENNSYLVANIA.

METHOD AND APPARATUS FOR HEATING LONG BLANKS.

Application filed May 26, 1922, Serial No. 563,748. Renewed February 5, 1925.

To all whom it may concern:

Be it known that I, WILLIAM B. PEIRCE, a citizen of the United States, and resident of Coraopolis, in the county of Allegheny 5 and State of Pennsylvania, have invented certain new and useful Improvements in Methods and Apparatus for Heating Long Blanks, of which the following is a specification.

10 My present invention relates more particularly to heating metal blanks, usually iron in "rod" form commonly obtainable in the market in "bundle coils" which are the product of rod rolling mills. The specific purpose in view is heating these rods to forging temperatures for continuous feed to automatic spike, screw, bolt or nut machines, but it will be obvious that the invention and various features thereof may 15 be employed for other purposes.

One of the specific objects is to heat the material by a continuous process whereby it is possible to continuously feed the material into, through and out of a heating 25 furnace without cutting the material into separate pieces or lengths. Preferably the blanks are as long as obtainable and where the above-described bundle coils are used successive coils may be electrically welded 30 end to end to maintain a continuous unbroken length of material continuously progressing through the furnace and to the forging machine.

Important features of my present method 35 include back-and-forth bending of the material to form suitably spaced lengths extending transversely of the direction of feed, preferably approximately parallel with each other and in substantially the same plane. Thus the material is compactly disposed, as it were, in a single horizontal layer, the height of which need be no greater than the thickness of the rod. Hence the furnace need be no higher 45 than is desired to insure uniform distribution of the heat and prevent too direct impingement of the heating medium upon the blank.

The number and length of the straight 50 portions thus connected by reverse bends is sufficient to afford supply material to the forging machine for a substantial period of time. Consequently, there is a wide margin for difference of rate at which the 55 bent material is supplied and the rate at which it is consumed by the forging ma-

chine and it is therefore possible to stop the bending machine and its supply coil long enough to put a new coil on the mandrel and weld its front end to the tail end 60 of the coil which has been exhausted.

From the above it will be evident that one broad purpose of the reverse bending method is to maintain a large amount of slack material in orderly non-twist formation between the forging machine and the source of supply, so that one of the elements, either the forging machine, or the supply mechanism, or a portion of the slack material between them, can be slowed up 65 or stopped for a short period, without interfering with the operation of the other element or elements.

By this method the rod may be bent in transversely extending lengths, passed 75 through the furnace for heating and then drawn off, straightened and forged, without putting in or taking out any longitudinal twist. The fibre will remain the same as in the original rod, and where rods or 80 bars of rectangular or other non-circular cross section are employed, as for instance flat bars for nut forging machines or square bars or rods for nail and spike making machines, the heated blank will go into the 85 forging machine flat, without any twist.

One specific purpose I have had in mind is employment of my method for heating of very heavy rods, say one inch square, 90 for forging heavy spikes.

The shaping of the rod or bar material in the required succession of reversely directed U-bends may be done by hand or by automatic mechanism, in any desired way, as for instance, by bending the material about forming or mandrel projections arranged on a periphery of a rotor. These may be sprocket-like projections spaced apart lengthwise of the rotor so that the straight portions of the rod between 95 the bends lie parallel with each other and with the axis of the rotor. If desired, automatic reciprocating means may be employed for laying and bending the material upon the rotary mandrel, the latter 100 being rotated step by step as the lengths are laid. Preferably stationary inclined surfaces or cams are arranged to automatically strip the bent material from the rotor and guide it to the furnace.

110 The material emerging from the furnace, being softened by the heat, is easily straight-

ened by traction in the feeding mechanism of the forging machine.

In the furnace the material preferably slides on track-like surfaces preferably 5 water-cooled pipes extending lengthwise of the bed of the furnace.

It will be obvious that the push-feed applied between the forming mechanism and the furnace, and the traction feed applied 10 between the furnace and the forging machine may be utilized for effecting the feed of the material through the furnace and the bed of the furnace may be suitably inclined downward from entrance to exit to utilize 15 gravity to assist the feed. Preferably, however, some auxiliary regularizing means is employed within the furnace. This could take the form of sprocket conveyors engag- 20 ing the reversely bent lengths of the blank but as shown herein the means em- ployed includes a system of ratcheting mechanism, comprising reciprocating bars provided with dogs which extend up into 25 the furnace and are pivoted and weighted so that on the rearward movement they trip and pass under the blank material but on the forward movement project, engage and feed the same.

The above and other features of my in- 30 vention may be more fully understood from the following detailed description in connection with the accompanying drawings, in which—

Fig. 1 is a top plan view indicating more 35 or less diagrammatically apparatus which may be used for practice of the method.

Fig. 2 is a side elevation partly in section on the line 2—2, Fig. 1.

Fig. 3 is an elevation looking in the direc- 40 tion of the arrows and on the line 3—3, Fig. 2.

Fig. 4 is a detail perspective view of part 45 of one of the end closing doors for the furnace.

Fig. 5 is a detail in vertical longitudinal section showing more clearly the construction of the feeding means indicated in Fig. 2.

While practice of the primary essentials 50 of the method require only the rod material, a man or means for reversely bending it and a heater through which the bent material is fed, I prefer to employ a furnace A, a bending form B, and feeding mechanism 55 C, all in operative relation to any desired automatic forging machine, diagrammatically indicated at D.

The furnace A may be of the ordinary 60 fire brick construction, supplied with flaming gases at very high temperature from any desired source, preferably a regener- 65 aging furnace such as is commonly employed for such purposes. The height of the furnace and the supply of the heating medium is preferably such that whatever

flame there is will flow along the roof without impingement on the material being heated, the heat transfer being mainly by reverberatory radiation from the highly heated roof. As the material travels along 70 or near the floor, the furnace does not have to be high. Its width will be determined more or less by the size and transverse strength of the material being heated. The heavier and stiffer it is, the longer the trans- 75 verse portions may be without danger of deformation during the heating and feeding operations. The length of the furnace will depend on how fast the material has to be supplied to the forging machine and how long it has to be exposed in the furnace to bring its entire cross section to uniform 80 forging temperature; also on how large a radius the bends must have in order not to deform the material too much for re- straightening when heated. Heavy ma- 85 terial requires larger radius bends, taking up more space lengthwise of the furnace. For most purposes the furnace need not be more than eight or ten feet long, on a width of six to eight feet, as where one 90 inch rod material is to be heated.

In Figs. 2 and 5, the bed of the furnace 95 1 has water-cooled pipes 2 on the surface thereof extending lengthwise of the furnace and affording slideways for supporting the rod material, preferably by engaging the spaced lengths 3 thereof and preferably at points well away from ends where they are connected through the reverse bends 4, 5. These pipes preferably diverge slightly so that their points of sliding contact with the material will shift as the latter moves for- 100 ward, thereby permitting uniform heating without formation of cold parts. More 105 than two slideway pipes may be employed if desired.

Extending lengthwise of the furnace bed 110 1 are slot-like recesses 6 in which are bars 7, slideable endwise in suitable supports 8, 9. These carry a series of dogs, each preferably 115 a single casting comprising feed finger 11, counterbalance 12, and a hook-like bearing 13, rotatably engaging a fixed stud 14 on bar 7. When bar 7 moves in the direction indicated by the arrow, Fig. 5, the dogs 120 contact with stops 15 on bar 7 and force forward feed movement of the rod material lengths 3. On the reverse movement each dog automatically trips and slides under the material, after passing which, the counter-weight 12 restores it to the vertical 125 position shown in Fig. 5. The bars 7 are reciprocated through links 17 by eccentric crank pins 18 on shaft 19 driven by sprocket chain or belt 20.

At the entrance and exit ends are doors 24, 25, which may be similar. These doors 130 are each vertically slideable, their operation being facilitated by counterweights 25',

operating through cord and chain 26, passing over pulley 27 and secured to the upper edge of the door, as at 28.

- In normal operation of the device these doors are maintained in the lowermost position and in order to permit the material to enter and leave the furnace, the lower portion of the door is preferably formed as a series of independent flaps 30 hinged or pivoted as at 31, so that they will automatically open and close when and to the extent that each is engaged by the rod material fed therethrough. These flap doors or other equivalent means are desirable as affording a moderate drag on the material to prevent more than one length at a time being dragged or forced out of the furnace and thereby becoming undesirably cooled before reaching the forging machine.
- The forming means B includes a rotor which, in this case, takes the form of heavy wheel-like members 35, 36, fixed on shaft 37 which is rotatably mounted in bearings 38. 35 has a series of stud projections with rollers 39, 39, projecting radially somewhat like the teeth on sprocket wheels. 36 has an equal number of similar projections 40, but they are located opposite points midway between the corresponding projections 39, 39, on the other wheel 35. The size of the stud rollers is preferably determined by the radius of curvature required for the bends of the rod, said rollers being preferably utilized as mandrels around which the rod is bent. In practice the diameter of the mandrel should be about three times the diameter of the rod in order that the bend may not be too sharp. The spacing of the rollers is preferably such that the straight lengths of the rod between them as at 3 are parallel. This, of course, requires that the axes of the rollers be distant from each other a distance equal to two diameters of the roller plus two diameters of the rod material. Obviously, however, exact parallelism of successive rod lengths is not necessary. Sharp bending is undesirable except in so far as it permits more rod lengths per unit length of furnace.
- The rod material may be laid on and bent upon the rotor, giving the metal a set in the shape shown, by hand or with the assistance of hammers, dies or forming tools. For the purpose of illustration I show a transversely sliding element adapted to apply and shape the rod material automatically. It consists of support 50 reciprocated on bed 51 by link 52 driven from any suitable source of power. Support 50 carries a standard 53 having a rear opening 54 for passage of rod material drawn from the idle drum or reel 55 rotatably mounted on vertical stud 56 on standard 57. The rod material is threaded through said opening 54, whence it passes through a guide opening 58 in a projection 59, the
- path of reciprocation of which is within the circle of rotation of the outer ends of the mandrel projections 39, 40. The throw of slide 50 is such as to bring 58, 59, endwise beyond 35 and 36 at each end of its travel. When the guide element 59 is thus beyond the end of the forming rotor the latter is rotated one step so that the return movement carries the rod material below the mandrel projection already engaged and above the next co-operating roller at the other end.
- This step by step movement with proper timing is caused by a double acting cam projection 60 on slide 61 which has a lost motion engagement with slide 50 through the medium of slot 62 and lug 63, as shown in Fig. 3. The slot 62 is enough longer than lug 63 to permit cam 60 lagging behind slide 50 until the latter can pass the mandrel rollers in both directions of travel. In the position shown in Fig. 3, the lug 63 has engaged the end of slot 62 and further movement in the direction of the arrow will move cam 60 into engagement with mandrel roller 40, thereby rotating 36 through an angle measured by the height of the cam and this distance is such that the return movement of slide 50 will carry the rod material below the roller, the upper side of which is already engaged by the rod material. On the return stroke, the cam 60 will lag behind in the opposite direction until lug 63 is in the other end of the slot and in position to give another step feed by operation on a stud roller of wheel 35.
- It will be noted that in the form shown there should be very considerable friction of the rod material where it passes through guide hole 58, in order to properly straighten, tense and set the rod material in the zig-zag form on the mandrel rollers. Obviously the parts will be designed to afford the drag required for this purpose and auxiliary forming or bending or guiding mechanism or rollers may be employed in this connection. Preferably stationary guides 66, 67, are arranged above the tops of the rollers 39, 40, to prevent accidental displacement of the bent rod material.
- Stationary inclined guides are arranged to strip the formed rod from the rotary mandrel and guide it to the furnace. No attempt is made to show the construction or means for positively operating the drawing out rolls diagrammatically indicated at E, nor the forging mechanism at D. It will be understood that the distances between the supply reel 55 and the forming mandrel B, as also the distance between the exit and the furnace and the drawing rolls may be considerably increased to give easier angles of draught, and that proportions, sizes and parts, may be otherwise varied; as found necessary or desirable.

I claim:

1. The method of heating long blanks in a relatively short wide furnace, which method consists in bending the blank reversely, at intervals, without twisting it, to form closely spaced lengths serially connected at the ends and lying approximately in the same plane; passing the thus bent material in a direction transverse to said lengths, into and through a suitable furnace to soften the same; and, while thus softened, straightening the bends.
2. The method specified by claim 1, with the further feature of withdrawing the material at the exit end of the furnace and passing it to a forging machine by and in accordance with the draft of the feed mechanism of said machine.
3. The method of forming long blanks for heating which consists in winding rod material back and forth successively around suitably spaced and sized mandrel projections, and stripping the bent material therefrom; then feeding the thus bent material transversely of the lengths thereof into operative relation to means for heating the same while thus bent and disposed in transverse lengths; then straightening the material while hot.
4. The method of forming metal articles of rod material without imparting twist thereto, which method consists in unrolling the material from the rod coil without imparting twist, bending it in parallel lengths, serially connected at the ends by reverse U-bends lying approximately in the same plane; passing the thus bent material in a direction transverse to said lengths, into and through a suitable furnace to soften the same; and, while thus softened, straightening the bends.
5. Apparatus for heating and forging rod material supplied in bundle coil form, comprising a rotatable reel from which the rod material is unrolled from the coil without twisting it; a rotatable mandrel having rod engaging and bending projections; a transversely reciprocated rod laying and bending element in operative relation between the reel and the mandrel; means for rotating the mandrel step by step after each length of rod has been laid thereon; means for stripping the bent rod material from the mandrel and guiding it to a heater and for feeding the thus bent material therethrough.
6. The apparatus specified by claim 5, and wherein the feeding means comprises dogs adapted to engage transverse lengths of the material and means for moving said dogs.
7. The apparatus specified by claim 5, in combination with drawing rolls and a forging machine at the exit end of said furnace.
8. A furnace for heating rod or bar material supplied to the furnace in continuous

reversely bent lengths lying in substantially the same plane and traction means for drawing said material from the exit end of the furnace by endwise draft thereon; said furnace having sectional end doors at the exit, extending across the width of the furnace whereby a drag is applied to said material and whereby only those door sections engaged by the material open and the others remain closed.

9. The method of preparing lengths of rod or bar material for supply to a draft mechanism which method consists in bending the material reversely at intervals without twisting it to form lengths serially connected at the ends and lying approximately in the same plane, and heating the successive lengths of the thus bent material thus maintaining in advance of said mechanism a supply of slack material in orderly formation and thereby rendering independent, within limits, the rate of supply of the material with respect to the rate of consumption by said mechanism.

10. The method of preparing lengths of rod or bar material for supply to a draft mechanism which method consists in bending the material reversely at intervals without twisting it to form lengths serially connected at the ends and lying approximately in the same plane, and heating the successive lengths of the thus bent material thus maintaining in advance of said mechanism a supply of slack material in orderly formation and thereby rendering independent, within limits, the rate of supply of the material with respect to the rate of consumption by said mechanism; and holding stationary the successive rear ends of the bent rod or bar material while welding thereto an additional length of material.

11. The method of preparing lengths of rod or bar material for supply to a draft mechanism which method consists in bending the material laterally to provide in advance of the mechanism a supply of slack material in orderly non-twist formation; heating the thus bent material and then straightening it while hot.

12. The method of preparing lengths of rod or bar material for supply to a draft mechanism which method consists in bending the material laterally to provide in advance of the mechanism a supply of slack material in orderly non-twist formation; heating the thus bent material and then straightening it while hot; and holding stationary the successive rear ends of the bent rod or bar material while welding thereto an additional length of material.

13. The method of preparing long blank material to maintain a slack supply to be removed at a desired rate, which method consists in bending the blank reversely, at intervals, to form transverse lengths, serial-

ly connected at the ends; heating the thus bent material and then straightening it while hot.

14. The method of maintaining a continuous supply of rod or bar material for the feed mechanism of an automatic forging machine, which method consists in supplying said material in separate lengths, each sufficient to supply the machine for a period greater than required to end-weld successive lengths; transversely bending each length being drawn upon by the feed mechanism, and heating the thus bent material; to establish a slack supply of such heated

material free to be drawn into said feed mechanism at the predetermined rate of consumption in the automatic forging machine, by merely straightening the bent portions; holding stationary the rear end of each length and end-welding thereto a succeeding length, while said slack supply is being thus drawn upon by straightening its bent portions.

Signed at North Tonawanda in the county of Niagara, and State of New York this 24th day of May, A. D. 1922.

WILLIAM B. PEIRCE.
